Patented May 9, 1961

190,286

TOY RIFLE

John W. Ryan, 11027 Cashmere St., Bel Air, Calif.

Filed Mar. 14, 1960, Ser. No. 59,707

Term of patent 14 years

(Cl. D34—15)

Fig. 5

Fig. 6

Fig. 1 is a side elevational view of a toy rifle showing my new design;

Fig. 2 is a top plan view;

Fig. 3 is a side elevational view of the opposite side shown in Fig. 1;

Fig. 4 is a bottom plan view;

Fig. 5 is a rear end view; and

Fig. 6 is a front end view.

The dominant features of the design reside in the portions shown in full lines.

I claim:

The ornamental design for a toy rifle, as shown and described.
